(57) **CLAIM**

The ornamental design for a kitchen hood, as shown and described.

DESCRIPTION

FIG. 1 is a top plan view of the front portion of a kitchen hood;

FIG. 2 is a front view of the front portion of a kitchen hood of FIG. 1;

FIG. 3 is a right elevation view of the front portion of a kitchen hood of FIG. 1;

FIG. 4 is a front perspective view of the front portion of a kitchen hood of FIG. 1;

FIG. 5 is a further front perspective view of the front portion of a kitchen hood of FIG. 1;

FIG. 6 is a front bottom perspective view of the front portion of a kitchen hood of FIG. 1;

FIG. 7 is a rear bottom perspective view of the front portion of a kitchen hood of FIG. 1;

FIG. 8 is a side perspective view of the front portion of a kitchen hood of FIG. 1; and,

FIG. 9 is a bottom view of the front portion of a kitchen hood of FIG. 1.

The broken line showing of the underside of a kitchen hood is included for the purpose of illustrating environmental structure and forms no part of the claimed design.
